ABRADING MACHINE

Arthur S. Johnson, Beverly, Mass., assignor to
 United Shoe Machinery Corporation, Borough
 of Flemington, N. J., a corporation of New
 Jersey

Application February 13, 1937, Serial No. 125,608

19 Claims. (Cl. 69—1)

This application relates to abrading machines and is herein illustrated and described as embodied in a machine suitable for roughing surfaces of channels formed on shoe soles. In United States Letters Patent No. 2,004,109, granted June 11, 1935 on the application of John B. Hadaway and also in United States Letters Patent No. 2,037,238, granted July 20, 1937 on the application of Charles G. Brostrom there are disclosed machines for performing this same operation. The machine disclosed in the present application, like the earlier machines above mentioned, is provided with a roughing tool in the form of a pair of rotary roughing brushes adapted to operate upon the channel lip and the base of the channel, respectively, and with a thin blade-like gage extending between the brushes for guiding the shoe by engagement with the shoulder of the channel, and also with a treadle-operated member for holding the channel lip against the roughing tool.

It is an object of the present invention to provide an improved machine of the type under consideration.

In accordance with a feature of the invention, the gage extending between the two roughing brushes is so mounted as to yield under pressure when the operator desires to press the shoe with greater than ordinary force against the roughing tool. In accordance with a further feature, yieldable means are provided for limiting the pressure which can be exerted through the treadle mechanism upon the member which holds the lip against the abrading tool. As illustrated herein, this lip-supporting member is also arranged to yield toward the roughing tool to enable the operator to apply the shoe with additional pressure against the tool. The lip-holding member of the illustrated machine is wedge-shaped to enable it to enter the space between the turned-over lip and the outer surface of the sole. The operator is thus enabled to exert pressure upon this member through the sole. In accordance with a still further feature the roughing tool comprises a pair of rotary brushes one of which has relatively stiff bristles for operating upon the channel base and the other of which has more flexible bristles for operating upon the lip.

These and other features of the invention including certain details of construction and combinations of parts will be described in connection with the illustrated machine and pointed out in the appended claims.

Referring now to the accompanying drawings,

Fig. 1 is a view in front elevation of the upper portion of the improved machine;

Fig. 2 is a view in end elevation of the parts shown in Fig. 1;

Fig. 3 is an enlarged showing of the roughing tool illustrated in Fig. 1;

Fig. 4 is an enlarged sectional view taken on the line IV—IV of Fig. 1; and

Fig. 5 is a detail view showing an element of a roughing tool in process of assembly.

The tool which performs the roughing operation comprises a roughing brush 10 having bristles which are relatively flexible for operating upon the inner surface of an opened channel lip and a roughing brush 12 having stiffer bristles for operating upon the base of the channel. In the illustrated construction the bristles of both brushes are of steel wire, the difference in flexibility being obtained by making the bristles of the brush 10 of a finer wire than those of the brush 12. The stiffer bristles of the brush 12 enable a relatively harsh abrading action to be performed upon the channel base to obtain the desired degree of roughness, while the more flexible bristles of the brush 10 operate yieldingly upon the thin material of the lip without danger of tearing or scouring through the lip. Referring to Fig. 3, this tool is seen in operation upon a shoe S having a channel lip L and a channel base B. The bristles of the brush 10 are mounted in a ring 14 while the bristles of the brush 12 are mounted in a ring 16. The rings 14 and 16 are both clamped upon a hub 18 by a nut 19 threaded upon the outer end portion of the hub. The brush 10 is provided with a pair of flanges 20 and 22 between which the bristles are confined and beyond which the bristles extend radially. The brush 12 has a similar pair of flanges 24 and 26, respectively. Between the adjacent flanges 22 and 24 of the brushes 10 and 12, respectively, is a spacing ring 28. The above-mentioned flanges and the spacing ring 28 are all assembled in proper relation to the rings 14 and 16 upon the hub 18 and clamped thereon by the nut 19. The hub 18 is provided with a flange 30 against which the assembly of brush members is clamped. It will be noted that in the illustrated machine the brush 10 which operates upon the channel lip is frusto-conical in form, while the brush 12 which operates upon the channel base is cylindrical.

The hub 18 with the brush member secured thereon is mounted upon the reduced end portion 32 of a shaft 34, being retained thereon against axial movement by the head of a screw 55.

36 which is threaded into the reduced end of the shaft. The hub 18 is retained against rotary movement relatively to the shaft 34 by a lug 38 extending from the reduced end of the shaft 5 into a slot formed in the hub 18.

The supporting structure of the machine will now be described. The shaft 34 is journaled in bearings 40 and 42 formed in a head 44 which is secured upon the upper portion of a column 10 46 of a suitable standard adapted to rest upon the floor. The shaft 34 at its opposite end carries a pulley 48 by which the shaft is driven from any suitable source of power. The head 44 has an upwardly and rearwardly extending 15 portion 50 in which is rigidly and fixedly secured a horizontal rod 52 which at its outer end carries a bracket 54. The bracket 54 is suitably bored to enable it to fit over the reduced end of the rod 52 and is clamped thereupon by a 20 pin 56 having a cylindrical concave portion for engaging the rod 52 and having a threaded end for a nut 58 by which the pin 56 may be tightened.

Loosely fitting within the space between the 25 adjacent flanges 22 and 24 of the brushes is a thin blade-like gage or guide 60 of arcuate form partially surrounding the shaft 34. The gage 60 is pivotally mounted upon a pin 62 (Fig. 2) which is secured in a depending portion 64 of 30 the bracket 54. Also mounted for rotation upon the pin 62 is a bracket 66 having a forked upper portion which embraces a pin 68 threaded into the bracket 54. Surrounding the outer portion of the pin 68 and interposed between an enlarged head on the end of the pin 68 and the bracket 66 is a coil compression spring 70 tending to urge the bracket 66 in a clockwise direction, as viewed in Fig. 2. Threaded through the bracket 66 is an adjustable stop screw 72 which is held in any desired position of adjustment by a lock nut 74. The end of the screw 72 engages a surface formed on the bracket 54 and thus determines the position of adjustment in which the bracket 66 is held by the spring 70.

Formed in the gage 60 is an arcuate slot 76 45 concentric with the pin 62 and adapted for engagement with an unthreaded portion of the shank of a clamping screw 78 which is threaded into the bracket 66 and which normally secures the gage 60 in fixed relation to the bracket. However, the gage 60 may readily be swung into an 50 out-of-the-way position, as shown in broken lines in Fig. 2, by loosening the screw 78. The gage 60 when secured for operation to the bracket 66 is held down by the spring 70 in a position adjustably determined by the stop screw 72. As 55 will later be pointed out, the spring 70 may yield to enable the operator to force the gage 60 upwardly whenever he regards a deeper or harsher abrading action desirable.

60 It will be noted with reference to Fig. 2 that the gage 60 has extending from its outer or work-engaging edge a salient portion 80. The operator normally holds the work against this salient portion, particularly when it is necessary to turn the shoe upon a short radius such as occurs at the toe portion, inasmuch as the shoe can more readily be pivoted around the relatively short salient portion 80. The outer edge of the gage might, in the absence of such a salient portion, 65 tend to impede such turning movement.

70 For holding the lip L against the brush 12 there is provided a wedge-shaped member 82 having a shank 84 which extends through an 75 opening formed in a bracket 86 and which is

adjustably secured in the bracket 86 by a pair of nuts 88 and 90 both threaded upon the shank 84. The bracket 86 is likewise provided with a threaded shank 92 which extends through an opening in the end of a lever 94 and is held 5 in any desired position of adjustment with respect to said lever by a pair of nuts 96 and 98 threaded upon the shank 92. The lever 94 is fulcrumed upon a pin 100 which may be secured in any desired position of heightwise adjustment 10 in a vertical slot 102 formed in a vertical web 103 extending from the bracket 54. The lever 94 has an upwardly extending arm 104 into which loosely extends a pin 106 which depends from a pair of ears 108 between which is pivotally mounted by means of a pin 110 carried by the ears 108 one end of an operating rod 112. It will be noted that when it is desired to swing the lever 94 to an out-of-the-way position for a purpose which will later be mentioned, the 20 rod 112, together with the ears 108 and the pin 106, may readily be lifted to free the arm 104. Upon the opposite end of the rod 112 are threaded a pair of nuts 114 and 116, each provided with a locking nut 118 and 120, respectively. The 25 portion of the rod 112 between the nuts 114 and 116 extends through an opening formed in an arm 122 of a bell crank which is fulcrumed upon a pin 124 secured in a bracket 126 carried by the rod 52. Surrounding the rod 112 and interposed 30 between the nut 114 and the arm 122 is a coil compression spring 128. A similar spring 130 also surrounding the rod 112 is interposed between the nut 116 and the arm 122. Suitable washers 132 are employed upon opposite sides of 35 the arm 122 to receive the thrust of the springs. The above-mentioned bell crank is provided with a horizontally extending arm 134 to which is pivotally connected the upper end of a treadle rod 136. The lower end of the rod 136 is connected 40 to a treadle of usual construction which is normally held up by a spring 138. A stop screw 135 adjustably threaded through the upper portion 45 of the bracket 126 and held by a lock nut 137 engages the arm 134 and thus limits the upward movement of the treadle rod 136 and determines the normal (i. e. non-operating) position of the lip-holding member 82. Downward movement of the treadle rod 136 is limited by a split collar 139 which is adjustably clamped on the rod 136 by a screw 141, the collar 139 being engageable with 50 an extension 143 of the bracket 126 through which the rod 136 passes.

55 Referring to Figs. 3 and 4, it will be observed that the lip-holding member 82, which has been described as wedge-shaped, is received into the space between the turned-over lip L and the outer surface of the sole of the shoe S. The upper surface of the wedge is identified by the reference character 140. The edge of this surface 140 which is first engaged by the advancing work is 60 relieved, as indicated by the reference character 142, to facilitate feed of the work. The lower surface of the wedge which is identified by the reference character 144 is convexly rounded to 65 facilitate feed of the work and manipulation of the shoe.

70 A guard 146 for protecting the shoe upper particularly in the vicinity of the shank is provided. This guard, as best shown in Fig. 1, is cone-shaped, having its large end open and closely adjacent to the bristles of the brush 12, and it extends over a sector sufficient to include the locality of operation of the brushes upon the shoe. The guard 146 depends from a bracket 75

148 to which the guard 146 may be secured in any desired position of horizontal adjustment. To this end the guard 146 is provided with a lug 150 having a horizontal slot formed therein through which extends a clamping screw 152 which is threaded into the bracket 148. The bracket 148 likewise is secured in any desired position of vertical adjustment in a bracket 154, the bracket 148 having a vertical slot 156 through which extends a clamping bolt 158 threaded into the bracket 154. The bracket 154 is mounted for horizontal adjustment in a direction perpendicular to the axis of the shaft 34 and to that end is slidably secured on a shelf 160 which extends horizontally from the bracket 54. The bracket 154 is secured in its desired position of adjustment by a screw 162 extending through a slot in the bracket 154 and threaded to the shelf 160. From the foregoing it will be evident that the location of the guard 146 can be adjusted in all three dimensions.

In order to dispose of dust arising from the roughing operation there is provided a dust hood 164 (the lower portion of which is shown as broken away, being indicated by broken lines) which surrounds the upper portion of the roughing tool and which is carried by a bracket 166 secured upon the rod 52. The hood 164 has an outer wall 167 which is hinged at 169 for upward swinging movement, the hinged wall being normally held down by a spring. The hood 164 leads into an exhaust conduit 168 of the usual suction system.

In order to keep the surface of the work free of dust which otherwise might accumulate thereupon there is provided a blast nozzle 170 directed in opposition to the rotation of the roughing tool. The nozzle 170 is located at the lower end of a pipe 171 which is supplied by a conduit 172 from a blower 174 having an inlet 176 and driven by a chain 178 from a sprocket wheel 180 on the shaft 34. The head 44 is formed to provide a housing 182 for the chain and sprocket, a detachable cover 184 being provided upon the opposite side. The blower 174 is secured upon a bracket 186 which is mounted for vertical adjustment on the head 44 and is secured thereon by clamping screws 188. The conduit 172 and the pipe 171 are held by a support 190 carried by a bracket 192 secured by a screw 193 to the bracket 54.

The arrangement for securing the bristles upon the rings 14 and 16 is shown in Fig. 5. This arrangement is the same for both rings, and while for purposes of illustration the reference character 14 has been applied to the ring of Fig. 5, everything shown in that figure is equally true in connection with the ring 16. Referring to Fig. 5, it will be noted that a bundle of bristles 194 has been looped to form two tufts. Extending radially through the ring 14 are a plurality of holes 196, the outer end portions 198 of which are counterbored to a larger diameter. A loop of a wire 200 is threaded outwardly through each of the holes 196, passed over the bight of the loop of bristles 194, and pulled tight to seat the bristles securely within the counterbore 198. When all of the counterbored holes have been filled with bristles in this manner the adjacent ends of the wire 200 are twisted together to secure the bristles permanently. An annular groove 202 is formed in the inner surface of the ring 14 to accommodate the wire 200. An advantage of mounting the brushes 10 and 12 upon separate rings 14 and 16, respectively, resides in

the fact that either brush when worn may be replaced without loss of the other brush. After the brushes 10 and 12 have thus been assembled upon the hub 18 they may be ground to the desired shape and diameter.

The operation of the machine will now be described. The operator, holding the shoe with the heel end away from him, inserts the end portion of the lip L between the member 82 and the brush 10 and bears downwardly upon the treadle, causing the member 82 to press the lip against the brush. He then feeds the shoe away from him, holding the shoe pressed upwardly and toward the right with the shoulder of the lip against the gage 60. The downward movement of the treadle is limited by the stop 141 and the pressure of the member 82 when the treadle is in its lowermost position is governed by the adjustment of the spring 128. If the channel flap has become warped and stiff by excessive drying the spring 128 will yield wherever necessary to prevent scouring through the flap. When the condition of the leather is such as to require greater than normal pressure against the brushes to obtain the same roughing effect or when a deeper abrading action is desired the operator presses the shoe upwardly against the gage 60 with a force sufficient to cause the spring 70 to yield. The upward pressure of the sole against the under surface 144 of the member 82 causes the member 82 to press the lip with greater force against the brush 10, for even although the collar 139 is against the stop 141 the yielding of the spring 128 will permit such further upward movement of the member 82. At the same time the yielding of the gage 60 enables the brush 12 to act with greater pressure upon the base of the channel. The guard 146 protects the upper of the shoe from damage, particularly at the shank portion.

It will be observed that the flap-holding member 82 may be angularly adjusted about its own axis by turning the shank 84 in the bracket 86 and it may also be angularly adjusted about the axis of the shank 92 by turning the shank 92 in the lever 94. Both adjustments are performed independently of the mechanism for swinging the lever 94 about the pin 100 to control the distance of the flap-holding member from the roughing brushes. The flap-holding member 82 moreover, may be adjusted for position in the direction of its own axis by making one or more complete turns of the threaded shank 84 in the bracket 86, and it may be adjusted in the direction of the axis of the threaded shank 92 by making one or more complete turns of the latter in the lever 94. In addition, a heightwise adjustment for the flap-holding member 82 is provided in the pin 100 and the slot 102. It is possible by reason of these adjustments to vary in all three dimensions the position which the flap-holding member will tend to assume under the influence of the treadle mechanism, and it is possible also to set the flap-holding member at any desired angle independently of its positional adjustment.

When regrinding of the brush is necessary the hub 18 is removed by taking out the screw 36. To facilitate removal of the brush, the pin 106 is withdrawn from the lever arm 104 which enables the member 82 to be swung upwardly out of the way. The hinged wall 167 of the dust hood is also swung upwardly out of the way.

Having thus described my invention, what I

claim as new and desire to secure by Letters Patent of the United States is:

1. A machine for roughing channels and channel flaps formed upon shoe parts, comprising a pair of roughing tools adapted to rough the channel flap and the channel base respectively of a channeled sole, means for supporting said tools in positions adjacent to each other to enable them to perform the said roughing operations, a gage engageable with the shoulder of the channel for guiding work presented to said roughing tools, and a support constructed and arranged normally to maintain said gage in a predetermined position relatively to said roughing tools and to yield under pressure of the work to enable the operator when he so desires to hold the work against said roughing tools with greater pressure than that permitted by the gage in its normal position. 5
2. An abrading machine comprising a frame, a driven shaft journaled in said frame, a pair of abrading tools mounted on said shaft and separated from each other axially by a relatively narrow space, a gage extending into the space between said tools for guiding work presented to said tools, said gage being mounted for movement toward and from the axis of said shaft, a stop for limiting the movement of the gage away from said axis, and resilient means for holding said gage yieldably against said stop, whereby the operator is enabled when he so desires to hold the work against said tools with greater pressure than that permitted by the gage in its stop position. 10
3. A machine for abrading channel flaps on shoe soles comprising an abrading tool constructed and arranged to operate upon one surface of a channel flap, a member engageable with the opposite surface of the flap to hold the flap against said abrading tool, means for urging said member toward said abrading tool to cause said member to press the flap against said abrading tool, and yieldable means for limiting the pressure which said urging means causes said flap-holding means to exert against the flap. 15
4. A channel roughing machine comprising a driven abrading tool constructed and arranged to operate upon the channel flap and the channel base of a channeled sole, a member engageable with the outer surface of the channel flap to hold the inner surface of the flap against said abrading tool, a treadle mechanism for urging said holding member toward said abrading tool to cause said member to hold the flap against the abrading tool, a stop for limiting the movement of said treadle mechanism in a direction to urge said holding member toward the abrading tool, and a spring associated with said treadle mechanism between said stop and said holding member to enable said holding member to yield. 20
5. A machine for abrading channel flaps on shoe soles comprising an abrading tool constructed and arranged to operate upon one surface of a channel flap, a member engageable with the opposite surface of the flap to hold the flap against said abrading tool, and means for urging said member toward said abrading tool, said urging means including a connection constructed and arranged to enable said holding member to be moved toward said abrading tool independently of said urging means. 25
6. A machine for abrading channel flaps on shoe soles comprising an abrading tool constructed and arranged to operate upon one surface of a channel flap, a member engageable with the
- opposite surface of the flap to hold the flap against said abrading tool, means for urging said member toward said abrading tool, and a yieldable connection including a pair of opposed springs arranged in said urging means to enable said holding member to yield both toward and from said abrading tool independently of said urging means. 30
7. A machine for roughing channel flaps on shoe soles comprising a roughing tool constructed and arranged to operate on one surface of a channel flap, a wedge-shaped member constructed and arranged to enter the space between a turned over channel flap and the outer surface of the sole from which the flap has been formed, means for urging said member toward said abrading tool to cause said member to hold the flap against the roughing tool, and a resilient connection in said urging means constructed and arranged to enable said wedge-shaped member to yield away from said roughing tool under excessive pressure and to yield toward said roughing tool when the operator exerts pressure through the shoe against a face of said wedge-shaped member. 35
8. A machine for roughing surfaces of channels on shoe soles comprising a rotary wire brush, a gage engageable with a channeled sole to position a surface of the channel in desired relation to said brush to control the normal pressure of the work against the brush, and a yieldable support for said gage constructed and arranged to enable the operator to press the work against said brush with greater than normal pressure. 40
9. A machine for roughing surfaces of channels on shoe soles comprising a rotary wire brush, a gage engageable with a channeled sole to position a surface of the channel in desired relation to said brush to control the normal pressure of the work against the brush, a spring for supporting said gage against the pressure of the work, and an adjustable stop against which said spring normally holds said gage, said spring yielding to enable the operator to press the work against said brush with greater than normal pressure. 45
10. A machine for roughing channel flaps on shoe soles comprising a roughing tool constructed and arranged to operate on the exposed surface of a turned over channel flap, a member engageable with the sole on which the flap is formed and also with the unexposed surface of the flap for supporting the flap against said roughing tool, a gage engageable with the sole to position the exposed surface of the channel flap in desired normal relation to said roughing tool, and supports for said gage and for said flap-supporting member constructed and arranged to yield under pressure of the sole as the operator presses the work toward the roughing tool with greater than normal pressure. 50
11. A machine for roughing surfaces of channels on shoe soles comprising a rotary driven roughing tool and a thin blade-like gage having an edge adapted for engagement with the shoulder of a channel to position the work relatively to said roughing tool, said work-engaging edge having a salient portion extending outwardly from said tool to facilitate turning of the work. 55
12. A machine for roughing surfaces of channels on shoe soles comprising a roughing tool constructed and arranged to operate on the exposed surface of a turned over channel flap, a member engageable with the unexposed surface of the flap to hold the flap against said roughing tool, and a support for said flap-holding member con- 60
- 70
- 75

structed and arranged for angular adjustment of said flap-holding member about two axes which are angularly disposed to each other.

13. A machine for roughing surfaces of channels on shoe soles comprising a roughing tool constructed and arranged to operate on the exposed surface of a turned over channel flap, a member engageable with the exposed surface of the flap to hold the flap against said roughing tool, and a support for said flap-holding member constructed and arranged for angular adjustment about two axes and also for locational adjustment of said flap-holding member in all three dimensions.

14. A machine for roughing surfaces of channels on shoe soles comprising a roughing tool constructed and arranged to operate on the exposed surface of a turned over channel flap, a wedge-shaped member for holding the channel flap against said roughing tool, said wedge-shaped member being constructed and arranged to enter the space between the turned over channel flap and the outer surface of the sole from which the flap has been formed, and yieldable means for maintaining said wedge-shaped member in an operative position relatively to said roughing tool, said position-maintaining means being constructed and arranged to enable the operator to exert pressure through the shoe and through the wedge-shaped member to press the channel flap against the roughing tool.

15. A support for holding a channel lip against a roughing tool comprising a generally wedge-shaped member adapted to be received between a turned over channel lip and the sole from which said lip extends and having an upper face for supporting the lip, which upper face has one of its edges relieved to facilitate feeding of the lip, and having also an under face for engagement

with the sole, said under face being convexly rounded in the direction of feed.

16. A machine for roughing surfaces of channels on shoe soles comprising a roughing brush having relatively stiff bristles for operation upon the base of a channel, a roughing brush having relatively flexible bristles for operation upon the flap of the channel, and means for guiding a sole in relation to said brushes.

17. A tool for roughing surfaces of channels on shoe soles comprising a pair of rotary brushes mounted in side-by-side relation upon a single hub, one of said brushes having relatively stiff bristles for roughing the base of a channel and the other brush having relatively flexible bristles for roughing the flap of the channel.

18. A tool for roughing surfaces of channels on shoe soles comprising a hub, a pair of rings slidably mounted on said hub for ready replacement and carrying elements for roughing the base of a channel and the flap of the channel respectively, said hub having a flange engageable with one of said rings, and means engageable with the other ring for exerting an axial clamping pressure through said rings against said flange to hold said rings securely upon said hub.

19. A tool for roughing surfaces of channels on shoe soles comprising a hub, a pair of brush rings slidably mounted on said hub for ready replacement and carrying wire bristles for roughing the base of a channel and the flap of the channel respectively, a spacing ring between said brush rings, said hub having a flange engageable with one of said rings, and a nut threaded on said hub for exerting an axial clamping pressure through all of said rings against said flange to hold said brush rings securely on said hub.

ARTHUR S. JOHNSON.
